ANGLE DENTAL HANDPIECE

Perry R. Skinner, Amsterdam, N. Y.

Application July 6, 1933, Serial No. 679,248

7 Claims. (Cl. 32—27)

This invention relates to means for detachably securing a tool in operative position in an angle dental handpiece.

In devices for the purpose as usually constructed, the attaching means are so formed and disposed that constantly during the rotation of a tool in use friction is imposed upon the attaching means. This is because the usual fastening means is attached to a non-rotatable part of the handpiece, and projects into a circumferential groove in the rotating tool, or otherwise engages the tool. Consequently, after any considerable use, the securing means becomes worn by reason of frictional contact with the tool, the tool is less rigidly held, and finally the securing means becomes inoperative. Any loosening of the tool in its holder allows of more or less wobbling of the tool and impairs its effectiveness, and frequently in practice, because of the wearing out of the attaching means, a tool is released in the mouth of a patient being operated upon, and there is danger of the tool lodging in the throat of the patient or of being swallowed.

One object of the present invention is to provide means for detachably securing a tool in an angle dental handpiece, whereby when in use the tool is directly secured to the driving means by which the tool is operated, dispensing with any intermediate device upon which friction is imposed. Further objects are to provide attaching means of the kind described in which a tool may be either secured or released by easy and rapid manipulation of the parts employed, and which is adapted for use in connection with tools having the standard form of shank.

Another object is to provide tool-attaching means in which the power applied to rotate a tool, operatively located in a handpiece, shall be utilized to insure a tool against possibility of removal during such rotation.

The invention resides in the generically and specifically novel features of construction and relative arrangement of coacting parts substantially as hereinafter described and claimed.

The present illustration of the invention shows one embodiment thereof, and an understanding of the principles of operation involved will make it clear that the forms and aggroupments of the elements employed may widely be varied without departing from the scope of inherent novelty.

In the drawing:

Figure 1 is a central vertical sectional view of the head of an angle dental handpiece, constructed in accordance with the invention, a tool being

shown introduced and in position to be attached and retained by the rotation of the securing means.

Figure 2 is a top plan view of the handpiece.

Figure 3 is a side view of a dental tool having a shank of standard form.

Figure 4 is a side view of a rotatable sleeve by which the tool-holding member of the device is received and driven, the wall of the sleeve being broken away to show a projection by which the tool-holding member is engaged, and which is adapted to secure a tool in operative position.

Figure 5 is a side view of the tool-receiving member.

Figure 6 is a transverse sectional view of the tool-holding member, the section being taken on the line 6—6 in Figure 5.

Figure 7 is a transverse sectional view taken on the line 7—7 of Figure 1.

In the form of the invention herein illustrated, the head of the angle dental handpiece is shown as consisting of a shell composed of two separable parts 1 and 2, each provided with an externally screw threaded extension 3 (shown by dotted lines in Figure 1), which extensions are received by and normally held in the interiorly screw threaded portion 4 of a shaft casing. By this construction ready separation of the parts to allow access to the interior of the head for purposes of repair, removal and substitution of parts, oiling, sterilizing, etc., is provided for.

Mounted in the head of the handpiece is a rotatable sleeve 5 which in general form corresponds to those commonly employed in similar structures. The sleeve 5 has on it a beveled gear 6 with which meshes a beveled pinion 7 on the end of a shaft 8, and by which rotation of the sleeve and parts connected is effected. The shaft 8 is driven in any suitable way, as by the usual flexible shaft employed in this connection. Extending from the inner face of the sleeve 5 is a projection 9, one function of which is to engage a tool-receiving member 10 and cause such member to rotate in unison with the sleeve.

The member 10, which is tubular in general contour and of a size to fit closely in the sleeve 5, has in it a lug or projection 11, which engages a flattened portion of the shank of a tool to be received and driven by the handpiece. The member has formed in it a transverse slot 12, which is intersected by a slot 13 which extends to the end of the member 10.

In assembling the parts the member 10 is introduced in position to cause the projection 9 of the sleeve 5 to pass through the slot 13, and engage

the wall of the slot 12, thus to be held normally in line with the slot 12. The parts are held in this position by a screw threaded ring or collar 14 which engages the screw threaded end of the member 10, and which bears on the end of the sleeve 5, thus preventing separation of the parts.

The opening in the head of the instrument is closed at its upper end by a cap 15 having a resilient extension 16, which latter is attached to the outer face of the head by a screw 17.

The novel parts of the handpiece, while capable of easy modification to adapt them for use in connection with any form of tool shank, are particularly adapted for use with what is recognized in the art as the standard form of this part. The

19 in the art as the standard form of this part. The shank, as shown in Figure 3, has near one end a recess of flattened portion 18 to be engaged by a part connected with the driving mechanism, to rotate the shank, and with a circumferential groove 19 to be entered by a member by which the shank is prevented from removal during the time the tool, of which the shank is a part, is in use.

Inasmuch as during the use of a handpiece of the kind described the driven sleeve 5 and the tool-receiving member 10 are constantly rotated in contact with portions of the instrument by which they are held in position, the consequent ultimate wear of contacting parts lessens or destroys the usefulness of handpieces, as ordinarily constructed. When the parts become worn, even slightly, wobbling of an attached tool ensues, rendering satisfactory operation impossible. In order to compensate for and to adapt the instrument to take up such wear of parts, the principal elements of the handpiece are given novel forms in order that adjustable cone bearings at the main contacting points may be provided. The end, which may be termed the lower end, of the tool-receiving member 10 is formed with a hollow head or enlargement 20 which is cup-shaped in general contour, and in which the inner face of the wall is inclined. The lower end 21 of the sleeve 5, which, when the parts are assembled, bears on the inclined face of the cup 20, is beveled to correspond to the inner contour of the cap. A cone bearing is furnished at the upper end of the tool-receiving member, by providing the inner face of the cap 15 with a cone-shaped projection 22 which enters and bears upon the upper end of the ring or collar 14. Any wear which may occur can readily be taken up by turning the ring or collar to raise it the required extent.

In assembling the operative elements of the handpiece the parts 1, 2 of the head are separated and the cylinder 5 is introduced into the lower section of the head with the bevel gear 6 in engagement with the pinion 7. The tool-receiving member 10 is then passed upwardly into the cylinder. As the member 10 is introduced it is turned to cause the portion 13 of the slot in its upper end to register with the projection 9 of the cylinder 5. The member is then pushed upwardly until the projection is in line with the portion 12 of the slot, and then given a partial rotation to secure it in place. After this the ring or collar 14 is applied to the upper end of the tool-receiving member, thus securing the cylinder and tool-receiving member in proper relative positions. The upper portion of the head is then placed in position, and the parts of the head are secured in place by screwing their screw threaded extensions 3 into the shaft casing 4. When the

parts are so placed the projection 22 of the cap bears upon the ring or collar 14.

The relative arrangement of the parts is such that when rotation is imparted to the cylinder 5 the tool-receiving member is positively driven by reason of the contact of the projection 9 of the cylinder 5 with the end of the slot 12. Consequently, when the shank of a tool is introduced into the tool-receiving member, and the lug 11 of the member enters the indentation 18 of the shank, the tool is positively driven, there being employed no intermediate connecting means involving frictional, spring or other unreliable features between the initial driving means and the tool shank.

So far as I am aware, it is novel, in organizations of the character herein described, to utilize by practicable, easily assembled parts the force exerted to rotate a tool, for the purpose of maintaining a tool in attached operative position. I have herein shown and described one form and disposition of parts to accomplish the purpose; but, of course, I am not limited in this respect. When the described parts are employed, and the shank of a tool is introduced to bring its indentation 18 to a position to receive the lug 11 of the tool-receiving member, the circumferential groove 19 of the tool shank is in line with the portion 12 of the slot in the tool-receiving member. Thus, assuming that the parts are in their proper initial relative positions, with the projection 9 of the cylinder 5 extending into the portion 12 of the slot in the tool-receiving member, and in line with the portion 13 of that slot, the application of power to rotate the cylinder 5 will cause the projection 9 to move to one end of the portion 12 of the slot to a position to drive the tool-receiving member, and at the same time to enter and travel a short distance in the groove 19 of the shank of the tool. When the parts are disposed as described not only will the tool be positively driven, but the force exerted to drive the tool effects and maintains a rigid locking in place of the tool continuously during its operation. The advantages of these two attainments will be apparent to any one who is familiar with the essential requirements of a positive driving of a tool, and of holding means, incapable of release, for maintaining a tool in place during use.

Release and removal of a tool, when the driving power is cut off, is easily accomplished by applying slight pressure to the cap 15, holding the tool-receiving member against rotation, and by turning the head and the cylinder 5 to its initial position with the projection 9 in line with the portion 13 of the slot in the cylinder. In this position, the projection is removed from the groove 19 of the tool shank and in line with the indentation 18 of the tool, permitting free withdrawal of the latter.

I claim:

1. A dental handpiece comprising a rotatable sleeve, a tool-receiving member, means for causing a tool to rotate with the member, and means whereby the tool receiving member is caused to rotate with the sleeve and a tool is engaged and prevented from withdrawal from the tool-receiving member. 65

2. A dental handpiece comprising a rotatable tool-receiving member having an interior lug adapted to engage a tool, and cause the latter to rotate in unison with the member, the tool receiving member being provided with a transverse slot, a driven sleeve receiving the tool-receiving member, and provided with a projection entering and

adapted to engage the end of the slot, and to engage and prevent the withdrawal of a tool.

3. A dental handpiece comprising a rotatable tool-receiving member, a lug extending from the member and adapted to engage a tool and cause it to rotate with the member, the tool-receiving member being provided with a transverse slot, and driving means including a projection adapted both to enter and engage an end thereof, and to engage and prevent the withdrawal of a tool.

4. A dental handpiece comprising a rotatable tool-receiving member having a transverse slot and a slot intersecting the transverse slot and extending to the end of the member, and driving means including a projection adapted to be passed through the intersecting slot to the transverse slot, to engage the end of the latter, and to engage and prevent the withdrawal of a tool located in the member.

5. A dental handpiece comprising a rotatable tool-receiving member, means for positively causing a tool to rotate with the member, the member being provided with a transverse slot and with a slot intersecting the transverse slot and extending

to the end of the member, and driving means including a projection adapted to enter the transverse slot and engage an end thereof, and to engage and prevent the withdrawal of a tool located in the member.

6. A dental handpiece comprising a head, a rotatable sleeve having a tapering end arranged in the head, a hollow tool-receiving member located in the sleeve and having a cup-shaped end having an inclined inner face, receiving the tapering end of the sleeve, and a cap attached to the head and having a cone-shaped extension entering and bearing on the end of the tool-receiving member.

7. A dental handpiece comprising a head, a rotatable sleeve having a tapering end arranged in the head, a hollow tool-receiving member located in the sleeve and having an adjustable ring at one end thereof, the other end being cup-shaped and having an inclined inner face, receiving the tapering end of the sleeve, and a cap attached to the head and having a cone-shaped extension entering and bearing on the adjustable ring.
